UNITED STATES PATENT OFFICE.

WILLIAM H. BRADT, OF TROY, NEW YORK.

ELECTRIC ALARM-GAGE.

SPECIFICATION forming part of Letters Patent No. 542,406, dated July 9, 1895.

Application filed February 23, 1894. Renewed May 8, 1895. Serial No. 548,581. (No model.)

To all whom it may concern:

Be it known that I, WILLIAM H. BRADT, a citizen of the United States, residing at Troy, county of Rensselaer, and State of New York, 5 have invented certain new and useful Improvements in Electrical Alarm-Gages, of which the following is a specification.

My invention relates to such improvements; and it consists of the novel construction and 10 combination of parts hereinafter described and subsequently claimed.

Reference may be had to the accompanying drawings, and the letters of reference marked thereon, which form a part of this specification. 15

Similar letters refer to similar parts in the several figures therein.

Figure 1 of the drawings is a plan view of the face of a gage provided with my improved 20 circuit-closing mechanism. Fig. 2 is a cross-section of same, taken on the broken line 2 2 in Fig. 1.

The object of my invention is to provide a circuit-closing mechanism for electrical 25 alarm-gages which can be easily applied to known forms of gage and which can be easily adjusted to automatically close the alarm-circuit when the gage-pressure reaches any pre-determined degree, high or low.

30 A is the case-wall of the gage which supports the operating mechanism. (Not shown.)

A' is the dial supported by the case, and A² the index fixed upon the shaft A³. The mechanism for operating the index may be of any 35 known form.

B is the cap or cover for the gage, comprising a metal rim B' and a glass B², together enclosing the dial and index. The cap is mounted upon the case-wall of the gage and is free 40 to rotate thereon.

C is a contact, forming one of the circuit-closing electrodes of the device, fixed upon and movable with the rim B' of the cap. The contact projects through an aperture in the 45 rim, interiorly of the gage, between the dial and the glass of the cap, and is insulated from the rim by the washer B³ of rubber or other insulating material interposed between the offset-attaching end C' of the contact and the 50 rim of the cap.

A binding-post D, secured by its attaching-shank D' to the rim in connection with the contact C, affords a means for connecting the contact with one of the battery-wires F. The 55 binding-post is insulated from the rim by the

insulating washers B⁸ B⁴, the attaching-screw B⁶ passing through both washers and an enlarged aperture in the attaching-shank of the binding-post, the head of the screw bearing upon the washer B⁴. 60

The inner end of the contact C is offset at C² into the path of the index A². A narrow strip C³ of insulating material is secured to the under side of the contact to insulate the same from the case-wall. 55

The index forms the other contact or electrode of the circuit-closing mechanism and may be connected with the other battery-wire F' by means of the binding-post D², fixed upon the case-wall at any convenient point, the 70 gage-case and intervening gage mechanism forming an electrical connection between the index and such binding-post.

The wires F and F' form part of an alarm-circuit comprising a battery and an electromagnetic alarm-bell, (not shown,) which may be of any known form. 75

When the gage mechanism has imparted sufficient movement to the index, the index engages the contact C, thereby closing the battery-circuit and operating the alarm device in such circuit. 80

The cap being rotary upon the gage-case and the contact C being secured to the cap, I am able by a rotary movement of the cap or rim to locate the contact at any desired point in the path of the index, the rotary cap affording a ready means for adjusting the contact. 85

My novel circuit-closing mechanism is applicable to various forms of gage having a rotary cap or cover. 90

The contact C may be insulated from the index in any known manner.

What I claim as new, and desire to secure by Letters Patent, is— 95

In an electrical alarm-gage, the combination with the index, of a cap having a rotary perforated rim, a contact insulated from such rim and fixed thereon to project through the rim-aperture into the path of the index, and means for connecting the index and contact with the battery-wires, substantially as described. 100

In testimony whereof I have hereunto set my hand this 22d day of February, 1894.

WM. H. BRADT.
